P. PERHÁTS

VEGETABLE SLICER, CUTTER, AND NUTCRACKER

Filed Aug. 17. 1922

Patented July 17, 1923.

1,462,148

UNITED STATES PATENT OFFICE.

PAUL PERHÁTS, OF CHICAGO, ILLINOIS.

VEGETABLE SLICER, CUTTER, AND NUTCRACKER.

Application filed August 17, 1922. Serial No. 582,361.

To all whom it may concern:

Be it known that I, PAUL PERHÁTS, a citizen of Hungary, residing at Chicago, in the county of Cook and State of Illinois, have invented certain new and useful Improvements in Vegetable Slicers, Cutters, and Nutcrackers, of which the following is a specification.

This invention relates generally to implements used in the comminution of food, having for an object the provision of a simplified form of device which may be used efficiently for slicing fruits, vegetables or other foods, and with which may be combined an attachment for cracking nuts or the like.

For further comprehension of the invention, and of the objects and advantages thereof, reference will be had to the following description and accompanying drawings, and to the appended claims in which the various novel features of the invention are more particularly set forth.

Fig. 1 of the drawings is an axial vertical sectional view of a fruit and vegetable slicing machine embodying the invention.

Fig. 2 is a plan view thereof.

Fig. 3 is an axial vertical sectional view showing a modified form of the invention in which a nut cracking attachment is provided in addition to the slicing means.

Fig. 4 is a plan view, omitting the supporting and driving means.

Figs. 5 and 6 are detail perspective views showing modified forms of slicing elements.

Referring now to Figs. 1 and 2 I provide a disk 10 rotatably mounted on a split stud 11 fixed on a bracket 12 having a channeled base element 13 adapted to engage the edge 40 of a table or other support, indicated at 14, the bracket being fixed on the table by a screw 15.

The disk 10 is provided with a series of radially extending knives 17 located adjacent slots 18 therein. These knives may be formed by sharpening integral elements struck out from the disk, or may be separately constructed and fixed in any suitable manner on the disk.

The disk 10 is adapted to be rotated by means of a pin wheel 20 fixed on a shaft 21 journaled in the bracket 12, the pins of the wheel engaging in holes 22 in the disk, the shaft 21 having a crank handle 23 thereon whereby it may be manually rotated. The split stud 11 is here arranged to form four

hooked prongs 24 having upwardly diverging adjacent sides and passing through a central aperture in the disk, the disk being removed when desired by first pressing the prongs together.

In use the object to be sliced or cut is held by one hand against the toothed vertical extension 12' of bracket 12, in contact with the disk 10 while the latter is rotated. The knives 17 successively engage the object and cutting slices therefrom, which fall through the slots 18 into a suitable receptacle such as 26.

In the modification shown in Figs. 3 and 4 a disk 30 having knives 31, is fixed on a heavy-rimmed wheel 32 mounted on a stud 34 fixed on a slide-block 35, the latter being

guided in a guide element 36 formed on a bracket 37. The slide-block is secured to the bracket by a set screw 38 adapted to be screwed into either one of a pair of tapped bores such as 39 in the bracket. The latter is provided with a channeled element 40 and clamping screw 41. Extending horizontally under the disk 30 is a shaft 43 on

which is fixed a pin wheel 44 adapted to engage either of the relatively small and large crown gear elements 45 and 46 formed on the underside of the wheel 32, the pin wheel being adapted to engage the small gear element when the device is used as a slicer. The shaft 43 is journaled at opposite ends in an upwardly projecting lug 37' on the bracket 37 and the slide-block 35, the latter being free to have longitudinal movement with respect to the shaft. A toothed vertical extension 37a of slide-block 35 is provided to guide the object to be sliced.

The nut cracking attachment comprises a flat circular head 50 loose on a spindle 51 fixed to an angular arm 52 removably secured to the bracket 37 by bolts 53, the perimeter of the head 50 passing closely adjacent that of the wheel 32, and being formed with a number of pockets 54. Fixed co-axially to the head 50 is a bevel gear 55 meshing with a smaller gear 56 on the shaft

43.

When the nut-cracking attachment is to be used the slide-block 35 is positioned to cause the pin-wheel 44 to engage the larger crown gear 46, and the angular arm 52, on which the head 50 and gear 55 are permanently mounted, is attached to the bracket

37, with gear 55 meshing with the gear 56 on shaft 43. The nuts to be cracked are

105

110

105

110

- placed in the pockets 54 and are cracked by being compressed between the latter and the rim of wheel 32 as the wheel and head are rotated by turning a crank 60 on shaft 43, the different gears being preferably so proportioned as to cause the outer faces of the nuts, which project beyond the pockets, to be moving at the approximate peripheral speed of the wheel 32.
- 10 When the nut-cracking attachment is not needed the arm 52 is removed, and the slide-block 35 is adjusted to bring the small crown gear 45 into engagement with the pin wheels 44.
- 15 In Fig. 5 I have shown a modified form of slicing element comprising a disk 10' having cutting elements 17' arranged in radial rows, these cutting elements being formed by pressing out tongues to leave slots 18'. This form of cutting element is particularly useful when a grinding or grating action is desired.
- In the modification shown in Fig. 6 a disk 10^a is provided with knives 17^a which differ from the knives 17 only in being crescent shaped instead of straight, slots 18^a being provided adjacent the knives, with this construction a shearing action of the knives on the material is obtained.
- 20 Having thus described my invention what I claim as new and desire to protect by Letters Patent of the United States is as follows:
1. A device of the class described comprising a heavy rimmed wheel, a bracket supporting said wheel, a rotary head supported by said bracket adjacent said wheel and having a number of pockets in its perimeter, a shaft adapted to rotate said wheel and head, slicer elements carried by said wheel, and means whereby said shaft may be caused to drive said wheel at relatively fast or slow speeds.
2. A device of the class described comprising a wheel, slicing means carried thereby, large and small crown gears formed on said wheel, a rotary head detachably mounted adjacent said wheel and having a pocket in its perimeter, a shaft extending under said head and wheel, gear connections between said shaft and head, a pin wheel on said shaft adapted to engage either of said large and small crown gears, and a bracket carrying said first wheel and adjustable longitudinally of said shaft to bring either of said crown gears into engagement with said pin wheel.
3. A device of the class described comprising a wheel, slicing means carried thereby, a rotary nut cracker adapted to be removably mounted adjacent the rim of the wheel to work in co-operation therewith, a shaft adapted to rotate said wheel and said nut cracker element, and means whereby said wheel may be driven at relatively fast or slow speeds by said shaft.

In testimony whereof I have affixed my signature.

PAUL PERHÁTS.
